UNITED STATES PATENT OFFICE.

OWEN T. SNYDER, OF COLUMBUS, OHIO, ASSIGNOR TO OWEN T. SNYDER & COMPANY, A FIRM COMPOSED OF OWEN T. SNYDER AND LOUIS F. FIESER, BOTH OF COLUMBUS, OHIO.

ELECTRIC SWITCH.

1,185,851.

Specification of Letters Patent.

Patented June 6, 1916.

Application filed November 11, 1914. Serial No. 871,608.

To all whom it may concern:

Be it known that I, OWEN T. SNYDER, a citizen of the United States, residing at Columbus, in the county of Franklin and 5 State of Ohio, have invented certain new and useful Improvements in Electric Switches, of which the following is a specification.

My invention relates to electric switches of the type wherein it is desirable to effect 10 a quick making and breaking of the circuit controlled.

The main object of my invention resides in providing a structure of this type wherein resilient means are provided for bridging 15 the gap in an open circuit, these resilient means being used in effecting the closure of the circuit and also for maintaining the circuit closed by a spring controlled contact member.

20 A further object of my invention resides in the provision of a push rod carrying a resilient extension which extension is so arranged that it operates upon the pivotally mounted contact closure control arm in such 25 manner that the spring extension bears on this arm on one side of its pivot point when in open position and upon the opposite side of this pivot point when in closed position.

30 My invention also resides in the specific structure shown, other objects resulting therefrom being more apparent after a further detailed description of the accompanying sheet of drawings, in which similar 35 characters of reference designate corresponding parts, and in which:

Figure 1 is a face view of my switch shown in closed position with the cover plate removed, Fig. 2 is a view similar to Fig. 1, 40 and showing the switch in open position, Fig. 3 is a section taken on line 3—3 of Fig. 1, and Fig. 4 is a section taken on line 4—4 of Fig. 3.

In carrying out my invention, I have provided 45 a casing member 1 of rectangular form preferably held closed by the cover structure shown at 2. This casing is provided with a plurality of openings to receive wire conducting conduits 3. Two of the conduits 50 shown in the present drawing are provided with wires 4, these wires leading into the switch casing and the circuits they control being closed by the operation of the switch mechanism as will now be described.

55 Slidably mounted in the end of the casing

1 is a push rod 5 carrying a handle or bearing knob 6. This push rod is suitably journaled in the boss 7 in the end of the casing and in the upstanding bearing member 8 so that only linear movement is possible. 60 This push rod is held in retracted position or the position shown in Fig. 2 by the interposition of the coiled spring 9 between the bearing member 8 and a shoulder element 10 securely mounted upon this push rod. At 65 its forward end there are attached two leaf springs 11 carrying bearing members 12 at their ends opposite from which they are attached, which bearing members are provided with rollers 13. These rollers 13 are designed to resiliently bear against arms 14 pivoted to the casing 1 intermediate their ends as is shown at 15. At the forward ends of these arms there is attached a small strip of insulation 16 which pieces of insulation 70 75 pivotally carry at their other ends contact or bridging members 17. These bridging members are of a length and shape to bridge the gap between each pair of binding posts 18 carried upon a suitable block of insulation 19 within the casing 1. It is to these binding posts that the incoming wires 4 are attached as is shown and movement of the contact members 17 to a position of engagement with these posts as is shown in Fig. 1, 80 85 will effect the closure of the circuits.

My invention is particularly applicable to circuits designed to be closed by such moving parts as elevator or other doors, etc., it being essential that the completion and 90 breaking of the circuit be effected very rapidly.

The manner of operation of my device is as follows, it being assumed two circuits are 95 under the control of the switch member as is shown, although it will be apparent that the use of two circuits is not essential to the practising of my invention. The leaf springs 11 are of such tension that the pivoted arms 14 will be held in the position shown in Fig. 100 2 when the push rod 5 is in its retracted position since the rollers 13 bear on the ends of the arms 14 beyond their pivot points 15. The movement of the push rod 5 to the position shown in Fig. 1 causes the resilient extensions to move forwardly in bearing relation on these pivoted arms to a position beyond their pivot point 14 as is shown in Fig. 1 and consequently changes the position of these pivoted arms. Inasmuch as 105 110

the contact or bridging strips 17 are pivotally mounted to the insulating strips 16, they will readily adjust themselves to a perfect contacting between each pair of binding posts 18 as is shown. The degree of pressure of these contact members upon their respective binding posts is of course determined by the tension exercised by the leaf springs 11. Release of the push rod from the position shown in Fig. 1 causes a breaking of the circuits thus made by the automatic action of the coil spring 9.

What I claim, is:

1. An electric switch comprising a casing, a push rod slidably mounted within said casing, resilient means for normally holding said rod in its outermost position, an arm pivoted intermediate its ends, yielding means carried by said rod arranged to bear on said arm on one side of its pivot point when said rod is in its outermost position and on the opposite side of said pivot point when said rod is in its innermost position, a pair of binding posts, and a contact member pivotally carried by one end of said arm and arranged to engage said posts when said rod is in one of said positions.
2. An electric switch comprising a casing, a push rod slidably mounted within said casing, resilient means for normally holding said rod in its outermost position, a double pair of spaced binding posts, the pairs located along opposite sides of said casing and on opposite sides of said rod, a pair of arms pivoted intermediate their ends and on opposite sides of said rod, a pair of resilient extensions on said rod arranged to bear on said arms on one side of their pivot points when said rod is in its outermost position and on the opposite side of said pivot

point when said rod is in its innermost position, and a contact member pivoted to each arm at a point between the posts of each pair of posts and arranged to engage the posts of each pair when said rod is in its 45 innermost position.

3. An electric switch comprising a push rod, guiding means for said rod, an engaging means on said rod, an arm pivoted intermediate its ends, said engaging means being arranged to bear on said arm on one side of its pivot point when said rod is in its outermost position and on the opposite side of said pivot point when said rod is in its innermost position, a pair of binding posts, 50 and a contact member pivoted to said arm at a point to lie between said posts and arranged to engage the posts when said rod is in one of said positions.

4. An electric switch comprising a push 60 rod, guiding means for said rod, and engaging means on said rod, an arm pivoted intermediate its ends, said engaging means being arranged to bear on said arm on one side of its pivot point when said rod is in a corresponding position and on the opposite side of said pivot point when said rod is in a corresponding position, a pair of binding posts, 65 and a pivotally supported contact member operatively mounted in connection with said arm to one side of its pivot point arranged to engage the posts when said rod is in one of said positions.

In testimony whereof I affix my signature in presence of two witnesses.

OWEN T. SNYDER.
